Primary Examiner — Kathleen L Jones(74) *Attorney, Agent, or Firm* — Zagorin Cave LLP; Robert W. Holland(57) **CLAIM**

I claim the ornamental design for a portable information handling system, as shown and described.

DESCRIPTION

FIG. 1 is a front perspective view of the portable information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a front perspective view thereof in an open position;

FIG. 9 is a rear bottom perspective view thereof in an open position; and,

FIG. 10 is a rear bottom perspective view thereof in a closed position.

Broken lines shown in the drawings illustrate portions of the portable information handling system, and form no part of the claimed design.

1 Claim, 8 Drawing Sheets(56)
